UNITED STATES PATENT OFFICE.

ARTHUR MIDDLETON ROSE, OF YONKERS, NEW YORK.

DESIGN FOR CARPET.

SPECIFICATION forming part of Design No. 27,794, dated October 26, 1897.

Application filed September 15, 1897. Serial No. 651,785. Term of patent 3¹ years.

To all whom it may concern:

Be it known that I, ARTHUR MIDDLETON ROSE, a citizen of the United States, residing at Yonkers, in the county of Westchester and State of New York, have invented and produced a new and original Design for a Carpet or other Fabric, of which the following is a specification, reference being had more particularly to the accompanying drawing, illustrating the same and forming part hereof.

The leading feature of my design is a floral pattern of groups of flowers connected by a scroll.

In the drawing, a is the body, b the border, and a b the complete carpet.

c are groups of flowers and flower forms, and d are scrolls connecting the same, the whole being arranged in a floral pattern, as shown.

The design of my invention will be best understood by reference to the drawing, and it may be expressed in any desired colors or combinations of colors and applied to velvet, Wilton, Brussels, or other carpeting.

What I claim as my invention, and desire to secure by Letters Patent, is--

1. In a design for a carpet, the body a, substantially as shown.
2. In a design for a carpet, the border b, substantially as shown.
3. The design for a carpet consisting of the body a, and border b, substantially as shown.

In testimony whereof I have hereunto signed my name in the presence of two witnesses.

ARTHUR MIDDLETON ROSE.
